JOHN HUBAND MACLEAN, OF ANN ARBOR, MICHIGAN.

SPRING-GUN.

1,237,928.

Specification of Letters Patent. Patented Aug. 21, 1917.

Application filed August 26, 1916. Serial No. 116,984.

To all whom it may concern:

Be it known that I, JOHN H. MACLEAN, a citizen of the United States, and a resident of Ann Arbor, in the county of Washtenaw and State of Michigan, have invented 5 a certain new and useful Improvement in Spring-Guns, of which the following is a specification.

My invention is an improvement in 10 spring guns, and the invention has for its object to provide a gun of the character specified, wherein spring controlled mechanism is provided for compressing a column of air to cause ejection of a projectile, and 15 wherein means is provided in connection with the gun for preventing the discharge of the projectile from the barrel, thus providing for a report without the discharge of a projectile, and wherein the retaining 20 means for the projectile is releasable to permit the discharge when desired.

In the drawings:

Figure 1 is a longitudinal section with the gun in inoperative position;

25 Fig. 2 is a similar view, with the parts in operative position, and ready for discharge;

Fig. 3 is a partial top plan view of the muzzle of the gun;

30 Fig. 4 is a section on the line 4-4 of Fig. 1, and

Fig. 5 is a perspective view of the improved gun.

In the present embodiment of the invention, 35 a barrel 1 is provided, which has one end closed, as indicated at 2, and is secured to a stock 3 of ordinary construction, the barrel being of metal and the stock of wood or the like. A cylindrical casing 4 is mounted 40 to slide longitudinally of the barrel, the said casing having an external annular rib 5 intermediate its ends, and having its inner end closed and extended beyond the barrel to form a second rib 6, while the outer end 45 is flared as shown at 7, to fit the barrel. Thus the casing may slide freely on the barrel, while it is guided by the ribs 5 and 6 and the flaring portion 7.

A plunger 8 is arranged within the barrel, and a stem or link 9 is connected with the plunger and extends through the closed end of the barrel and connects with trigger mechanism to be described. A coil spring 10 encircles the stem 9 beneath the plunger 8, and the closed end of the casing, and normally acts to force the casing inwardly toward the closed end of the barrel. A grip

or handle 11 is mounted to slide on the under side of the barrel, toward and away from the muzzle, and a ring 12 is connected 60 with this grip, the said ring encircling the casing between the ribs 5 and 6. The ring is a split ring having radial lugs 13 at its ends, which are received in a recess in the grip 13, and rivets, as shown in Fig. 4, are 65 passed through the grip and the lugs to connect the ring and the grip. The lugs pass through a slot 14 which extends longitudinally of the barrel, and by means of the grip the casing may be moved toward the 70 muzzle of the barrel to compress the spring, as shown in Fig. 2.

When the spring has been compressed by moving the casing toward the muzzle, as shown in Fig. 2, the parts may be locked 75 in this position, by the engagement of a notch 15 on the stem with the closed end of the casing, merely by lowering the inner end of the link. This notch 15 has a catch 80 which engages the outer face of the head of the link at the opening for the stem to lock the parts in set position. The inner end of the link or stem has a pin and slot connection with a trigger bar 16 which is arranged in a vertical opening 17 in the stock, and the 85 lower end of the said trigger bar is adapted for engagement with one of the arms of an angular trigger 18 pivoted within the enlarged lower end of the opening 17. One of the portions of the trigger 18 extends 90 below the stock, in position for engagement by the finger of the operator, to move the trigger bar upwardly and cause the same to lift the link and release the notch 15 from the casing. When this occurs, the casing 95 will be forced back into the barrel by the spring 10, in the position of Fig. 1, and with a projectile in the outer end of the casing forming a stop at this point, it will be evident that a body of air will be compressed between the plunger and the projectile sufficient to cause the discharge of the projectile from the casing with a loud 100 report.

Means is provided for preventing the discharge of the projectile from the barrel, the said means consisting of a retaining pin 19 which is passed through registering openings at the muzzle of the gun, the said pin having a head for limiting its downward movement through the openings to a position transverse to the barrel, and a retaining plate 20 is provided for preventing accidental disengagement of the pin. The said 105

plate is pivoted to the barrel at the muzzle, as indicated at 21, and near its other end the said plate is concaved as shown at 22, to engage over the head of the pin. It will be noticed from an inspection of Figs. 1 and 2, that the projectile 23 is frusto-conical, but is arranged with its base toward the retaining pin and that the inner end of the said projectile is further beveled or inclined to facilitate the engagement of the said inner end of the projectile with the flaring portions of the casing.

In operation, with the parts in the position of Fig. 1, the operator will move the grip toward the muzzle until the notch 15 of the link engages the end 6 of the casing and locks the parts in such position. The grip may now be moved backwardly toward the stock if desired, or it may remain in the position shown in Fig. 2. As the casing is moved forwardly by the grip, the flaring end of the casing will engage the small end of the projectile, and the projectile will be forced into the casing by the forward movement of the casing as long as the retaining pin 19 holds the projectile from moving outwardly.

When the operator desires to shoot, he will pull the trigger 18. The trigger will lift the trigger bar 16 and the inner end of the stem 9, thus releasing the link from the casing, and the expansion of the spring will force the casing inwardly. The air between the projectile and the plunger 8 will be compressed to such a degree that before the casing reaches the end of its inward movement, the projectile will be discharged therefrom with a loud report. When it is desired to use the gun for target practice, for instance, the retaining pin may be removed, and it will be evident that when so removed, the projectile will be discharged.

I claim:—

1. A spring gun comprising a barrel and a stock to which the barrel is connected, a casing mounted to slide longitudinally of the barrel and having the end adjacent to the muzzle of the barrel open, a plunger in the casing and having a stem extending through the inner end of the casing and of approximately the same length as the casing, a spring between the plunger and the inner end of the casing, the stem having a catch for engaging the casing to hold the spring compressed, means at the inner end of the stem for moving the same to release the catch and for holding the plunger from movement by the spring, means outside of the barrel for moving the casing toward the muzzle to compress the spring, the outer end of the casing being flaring to engage a tapering projectile when the casing is

moved outwardly, and releasable means at the muzzle of the barrel for holding the projectile to cause the casing to engage the same.

2. A spring gun comprising a barrel and a stock to which the barrel is connected, a casing mounted to slide longitudinally of the barrel and having the end adjacent to the muzzle of the barrel open, a plunger in the casing and having a stem extending through the inner end of the casing and of approximately the same length as the casing, a spring between the plunger and the inner end of the casing, the stem having a catch for engaging the casing to hold the spring compressed, means at the inner end of the stem for moving the same to release the catch and for holding the plunger from movement by the spring, and means outside of the barrel for moving the casing toward the muzzle to compress the spring.

3. In a spring gun, a barrel, a casing mounted to slide in the barrel, a spring normally forcing the casing inward, a plunger in the casing fixed with respect to the barrel, means for holding the casing in outward position with the spring compressed, said means being releasable, means outside the barrel for moving the casing against the resistance of the spring, the outer end of the casing being adapted to receive a projectile for closing the said casing, and forming with the plunger a closed air chamber in the casing, the outer end of the casing being flaring to engage a tapering projectile, and releasable means at the muzzle of the barrel for holding the projectile.

4. In a spring gun, a barrel, a casing mounted to slide therein, a spring normally pressing the casing inward, a trigger mechanism for holding the gun in outward position with the spring compressed, the outer end of the casing being adapted to receive a projectile for closing the said casing and forming with the plunger a closed air chamber in the casing, releasable means at the muzzle of the barrel for holding the projectile to permit it to be forced into the barrel by the movement of the barrel forwardly, and means for moving the barrel.

5. In a gun, the combination with a barrel, of a cylinder movable within said barrel, an abutment, a stopper for fitting said cylinder having a free movement within the barrel limited by said abutment, means for reciprocating said cylinder to press the same into engagement with said stopper while seated on said abutment and to carry the same rearward, and a piston co-operating with said cylinder to compress the air and eject the stopper.

JOHN HUBAND MACLEAN.
